UNITED STATES PATENT OFFICE

AUGUST E. MUELLER, OF CHICAGO, ILLINOIS, ASSIGNOR OF ONE-THIRD TO THOMAS J. HRUBY AND ONE-THIRD TO JOHN O. HRUBY, JR., BOTH OF CHICAGO, ILLINOIS.

BURNER FOR STEAM BOILERS AND SUPERHEATERS.

1,226,570.

Specification of Letters Patent. Patented May 15, 1917.

Application filed June 9, 1916. Serial No. 102,627.

To all whom it may concern:

Be it known that I, AUGUST E. MUELLER, a citizen of Argentina, South America, residing at Chicago, in the county of Cook and State of Illinois, have invented certain new and useful Improvements in Burners for Steam Boilers and Superheaters; and I do hereby declare that the following is a full, clear, and exact description thereof, reference being had to the accompanying drawings, and to the characters of reference marked thereon, which form a part of this specification.

This invention relates to improvements in burners for steam boilers and superheaters or both, adapted to be heated by a liquid fuel such as crude petroleum or petroleum distillates combinable with a gaseous oxygen carrier.

20 Among the objects of the invention is to provide a burner for this and analogous purposes, which is simple and economical in design and which is economical to operate and so arranged as to readily adapt itself to a compact boiler structure so as to occupy small space and to be highly efficient for producing steam.

Other objects of the invention are to provide an arrangement of a burner or furnace with a boiler or boiler and superheater so arranged as to enable the parts to be very compactly assembled and to efficiently apply the heated products of combustion to the surfaces of the boiler and superheater, and 35 the invention consists in the combination and arrangement of the parts shown in the drawings and described in the specification and is pointed out in the appended claims.

40 As shown in the drawings:—

Figure 1 is a vertical sectional view of a boiler embodying my invention.

Fig. 2 is a plan view thereof, with the parts broken away.

45 In said drawings, 10 designates the shell of the boiler which, preferably and as herein shown, is made oblong and is provided with a top wall 11 and a bottom wall 12. 14 designates a burner arch arranged within 50 the shell 10 and which constitutes the inner wall of the boiler, to which latter wall heat is applied to heat the water in the boiler. The said burner arch is largest at its bottom, is flanged at its upper and lower ends 55 to fit the upper and lower walls, respectively,

of the boiler shell and is attached thereto by rivets 15, or other suitable fastening means, to produce water-tight joints. The upper end of said burner arch is formed with a neck portion 17 which is open to the space above the boiler. Surrounded by the flanged lower end of the burner arch is a central opening 18 through which the burner, hereinafter to be described, extends.

The boiler 10, as herein shown, is of the flue type, vertically arranged flues 20, 20 extending between the top and bottom walls of the boiler and being flanged thereover, or otherwise fastened thereto. The boiler may be strengthened by two or more external double flanged ribs 22, 22 which extend around the same and are riveted thereto. Said boiler may be supported by an open frame 24 through the medium of brackets or lugs 24'. Said frame 24 may rest on any suitable supports, as the I-beams 25 herein shown.

The flues 20 are provided with a series of heat radiating fins 26 which extend into the water space of the boiler, and said water space may, if desired, be filled or partially filled with a mass of heat-conducting filaments, such, for instance, as is shown in my copending application for United States Letters Patent Serial No. 96,750, filed on the 11th day of May, 1916.

29 designates a superheater chamber which is arranged above the boiler, and centrally over the neck or throat 17 of the burner arch. Said superheater chamber, as herein shown, comprises upper and lower convex plates 30, which are attached together at their edges by rivets 31 or other suitable fastening devices. Any suitable packing may be interposed between said marginal portions of the plates to provide steam-tight joints. The plates are further reinforced by stay bolts or rods 32 which extend between and are fastened to the plates. Dry steam is conducted from the superheater through an outlet pipe 34, and preferably the mouth of said pipe is provided with a screen 35 to prevent solid particles from passing out of the superheater chamber with the dry steam. The said superheater chamber is connected to the steam space of the boiler through the means of a plurality of connecting tubes 36 which extend between the top wall 11 of the boiler and the lower plate 30 of the superheater 110

and are upset or otherwise secured to said parts to produce steam-tight joints.

The boiler and superheater chamber are protected from the surrounding cooler air by means of a housing 38 which is open at its bottom and is closed at its top by a wall 39, the latter having a suitable opening for the passage of the dry steam pipe 34. The said housing is herein shown as supported 10 on a boiler by means of brackets or lugs 40 attached to the inner sides of the housing and adapted to rest upon the lower reinforcing ribs 22 of the boiler.

The water in the boiler is heated, and 15 heat is applied to superheat the steam thereby produced, by a form of liquid-fuel burner which is specially adapted to conform to the combination of the boiler and superheater elements, and which is made as follows:

45 designates a floor plate which is also supported on the members 25 and is preferably attached, as by means of brackets 46, to the supporting frame 24. Said floor 25 plate is provided with numerous openings to permit air to pass freely upwardly there-through. It is also provided centrally with a raised portion 48 and is formed between the portion 48 and the lower level thereof 30 with an intermediate platform 49. The raised dome-like portion 48 is provided with a central starting burner 50 to receive a liquid fuel supply pipe 51. The intermediate raised platform 49 supports a perforated 35 fuel mixing chamber 53, centrally into which said starting burner extends. 54 designates a perforated dome of general conical shape, the larger lower end of which is arranged outside of the larger lower end of 40 the mixing chamber wall and the upper end of which extends into the hollow fire arch. The wall of the dome 54 preferably coincides in curvature with the wall of the burner arch. The arrangement is such that 45 there is formed between said dome and mixing chamber a passage 55 and between said dome and arch a combustion chamber 56. The said dome terminates at its upper end in a neck portion 57, which is surmounted by 50 a hollow burner head 58 that is arranged just below the lower plate 30 of the superheater 20. The upper wall of said head 58 is preferably solid or imperforate and said head is provided at its periphery and on its 55 lower side with burner openings 59 through which the fuel mixture may pass laterally from the burner head, and, upon ignition, to constitute a flat horizontal flame body which is distributed beneath and impinges against 60 the lower wall of the superheater.

Fuel is supplied to the mixing chamber 53 through a pipe 60. An oxygen-bearing medium, such as air or steam, for admixture with the liquid fuel, is also supplied to said 65 mixing chamber, and, conveniently, and as

herein shown, the oxygen-bearing medium may be delivered thereto through a pipe 61 which surrounds the fuel pipe 60. Arranged within the mixing chamber above the starting burner 50 is a rotary mixing element, having the form of a fan 63, the shaft 64 of which is rotatively mounted in a suitable bearing in the upper wall of the mixing chamber. The said fan 63 is located in the path of the incoming fuel delivered 70 through the pipe 60 and also in the path of the oxygen-bearing medium under pressure, so that the fan is rapidly rotated while the fuel and oxygen-bearing medium is delivered to the mixing chamber, with the effect 75 to intimately intermingle the constituents of the fuel so as to produce a free burning mixture. The intermixed fuel constituents are discharged through the perforations of the walls of the mixing chamber into the 80 dome 54, and are by said dome further broken up or intermingled and distributed to the annular space 56 where they are ignited, the heat of the products of combustion impinging against said arch. A portion of the mixture is directed through pipes 67, which lead from the space 55, into one or more annular burner pipes 68 which are arranged beneath the boiler around the central raised platform 49, said pipes discharging the mixture through perforations at the upper sides thereof toward the bottom of the boiler. The mixture is ignited in the combustion chamber above said pipes and the products of combustion play against the lower wall 85 of the boiler and escape upwardly around the boiler and through the burner arch and boiler flues.

Air may be directed to the burners through the perforated floor plate 45 and through openings 70 formed in the supporting frame 24. The products of combustion may be directed from the boiler casing or housing 38 in any suitable or preferred manner. As herein shown, said housing is provided at its top wall with an outlet pipe 71, through the medium of which the products of combustion may be drawn off from the casing or housing. The housing 38 will preferably be provided with a suitable insulation lining 72 to prevent radiation of heat from the boiler. In smaller boilers, adapted to tractors or other vehicle uses, the insulation may be asbestos, and for larger stationary boilers it may be fire brick or the like.

In the operation of the boiler, after the boiler has been filled with water, through any suitable means not necessary to be herein shown, the valve of the starting burner pipe 125 51 is opened to deliver fuel to the burner 60. The burner 50 may be supplied with a relatively light petroleum distillate, such as gasoline, and oxygen to start the flame may be supplied by any suitable form of blow pipe 130

After the walls of the mixing chamber 53 have become heated, the valves of the fuel and air or steam delivery pipes 60, 61, respectively, are opened, and the air, or other oxygen-bearing medium, under pressure is delivered against the mixing fan 63 with such force as to rapidly rotate it and thereby intimately intermix the liquid fuel with the combustion supporting oxygen. This mixture fills the dome 54. A portion of it is carried by the pipes 67 into the connected burner pipes 68 where it is ignited to produce a flame which plays on the bottom wall of the boiler, and escapes upwardly around the outer side of the boiler and through the flues and combustion chamber 56. A portion of the mixture also escapes through the perforated dome 54 into the passage 56 where it is ignited to play upon the arch 14. A further portion of said mixture is carried through the perforated head 58 and is ignited at the discharge openings 59 to directly heat the superheater chamber or casing. The products of combustion 25 from the chamber 56 also pass beneath and around the superheater chamber and among the connecting pipes 36. The heat thus delivered from the burner serves to raise the temperature of the water to produce steam and also to superheat the steam after it passes from the steam space of the boiler into the superheater chamber, so that the steam delivered through the pipe 34 is a dry superheated steam.

35. It will be noted that the construction of the boiler and superheater and the construction of the burner are such as to peculiarly inter-adapt one to the other and is such as to apply the heat of the burning mixture 40 to the heating surfaces of the boiler and superheater in a manner to derive the maximum benefit of the heat in the production of dry superheated steam. It will be furthermore observed that the construction 45 of the inter-related parts of the boiler and burner is such as to enable the parts to be very readily assembled and to be produced by simple machine operations, and further, to produce a very compact boiler construction.

I claim as my invention:—

1. A burner for a steam boiler comprising a burner arch arranged to constitute the inner wall of the boiler and open at its top and bottom; a perforated fuel mixing chamber centrally below said arch; a perforated mixing and distributing dome surrounding the mixing chamber and extending into the arch to provide between said chamber and dome an annular passage and between the dome and arch a combustion chamber; means for directing liquid fuel and oxygen to the mixing chamber and for mixing the fuel constituents therein; a burner pipe 55 below the burner arch and communications be-

tween said burner pipe and said annular passage.

2. A burner for a steam boiler comprising a burner arch arranged to constitute the inner wall of the boiler and open at its top and bottom; a perforated fuel mixing chamber centrally below said arch; a perforated dome surrounding the fuel mixing chamber and extending into the arch, to provide between the same and said arch a combustion chamber; means for directing fuel constituents to the mixing chamber and for mixing the fuel constituents therein; a burner pipe below the arch around the mixing chamber with means to direct burning mixture there- 70 to from the mixing chamber.

3. A burner for a steam boiler and superheater comprising a burner arch open at its top and bottom; a perforated fuel mixing chamber arranged centrally below said arch; a perforated dome surrounding the fuel mixing chamber and extending into the arch, with a combustion chamber between the dome and arch; means for directing fuel constituents to the mixing chamber and for 75 mixing them therein, and a burner head extending upwardly from said dome and through the open upper end of the burner arch to heat a superheater.

4. A burner for a steam boiler comprising a burner arch arranged centrally of the boiler and open at its top and bottom; a perforated fuel mixing chamber arranged centrally below said arch; a perforated dome surrounding the fuel-mixing chamber 80 and extending into the arch to provide between said chamber and dome an annular passage and between the dome and arch a combustion chamber; means for directing fuel constituents to the mixing chamber and for 85 mixing them therein; a burner pipe or pipes surrounding said mixing chamber below the arch, and pipes connecting said burner pipes with the annular passage between the mixing chamber and said dome.

5. A burner for a steam boiler comprising a burner arch constituting the inner wall of the boiler and open at its bottom and at its top; a mixing chamber at the lower open end of said arch; a perforated dome surrounding said mixing chamber and extending into said arch; a liquid fuel supply pipe leading into the mixing chamber; an oxygen-bearing medium supply pipe leading also into said chamber, and means 95 within the chamber for mixing the fuel constituents.

6. A burner for a steam boiler comprising a burner arch constituting the inner wall of the boiler and open at its bottom and at its top; a mixing chamber at the lower open end of said arch; a perforated dome surrounding said mixing chamber and extending into said arch; a liquid fuel supply pipe leading into the mixing chamber; 100

an oxygen-bearing medium supply pipe leading also into said chamber, and a rotative mixing fan located within said mixing chamber against which the fuel constituents under pressure are directed.

7. A burner for a steam boiler comprising a burner arch constituting the inner wall of the boiler and open at its bottom and at its top; a mixing chamber at the lower open end of said arch; means to conduct fuel mixture from the mixing chamber to the bottom of the boiler and to the burner arch; a liquid fuel supply pipe leading into the mixing chamber; an oxygen-bearing medium supply pipe leading also into said chamber; a rotative mixing fan located within said mixing chamber against which the fuel constituents under pressure are directed, and a starting burner within said mixing chamber located beneath said fan.

8. A burner for a steam boiler comprising a burner arch constituting the inner wall of the boiler and open at its bottom and at its top; a mixing chamber at the lower open end of said arch; a burner pipe or pipes at the bottom of the arch; means to conduct fuel mixture from the mixing chamber to said burner pipes; a liquid fuel supply pipe leading into the mixing chamber; an oxygen-bearing medium supply pipe leading also to said chamber; a rotative mixing fan located within said mixing chamber against which the fuel constituents under pressure are directed, and a perforated dome surrounding said mixing chamber and extending into said burner arch and forming between the same and the mixing chamber an annular passage through which the fuel mixture is conducted to said burner pipes, and forming also between the dome and the arch a combustion chamber.

9. A burner for a steam boiler comprising a burner arch constituting the inner wall of the boiler and open at its bottom and at its top; a mixing chamber at the lower open end of said arch; a burner pipe or

50 pipes at the bottom of the arch; means to conduct fuel mixture from the mixing chamber to said burner pipes; a liquid fuel supply pipe leading into the mixing chamber; an oxygen-bearing medium supply pipe leading also to said chamber; a rotative mixing fan located within said mixing chamber against which the fuel constituents under pressure are directed, a perforated dome 55 surrounding said mixing chamber and extending into said burner arch and forming between the same and the mixing chamber an annular passage through which the fuel mixture is conducted to said burner pipes, 60 and forming also between the dome and the arch a combustion chamber, and a superheater burner head arranged centrally above said combustion chamber in open communication with said dome.

10. A burner for a steam boiler comprising a burner arch constituting the inner wall of the boiler and open at its bottom and at its top; a mixing chamber at the lower open end of said arch; a burner pipe 70 or pipes surrounding and arranged below said mixing chamber; a liquid fuel supply pipe leading into the mixing chamber; an oxygen-bearing medium supply pipe also leading into said chamber; a perforated 75 dome surrounding the mixing chamber and extending into said burner arch and forming between the same and the mixing chamber an annular passage through which the fuel mixture is conducted to said burner 80 pipes, and forming also between the dome and the arch a combustion chamber, and a hollow neck extending upwardly from the dome and surmounted by a burner head.

In testimony whereof, I have hereunto set 85 my hand at Chicago, Illinois, this 1st day of June, 1916.

AUGUST E. MUELLER.
